UNITED STATES PATENT OFFICE.

CHARLES A. CLARK, OF HARTFORD, CONNECTICUT, ASSIGNOR TO TRUMBULL ELECTRIC MANUFACTURING COMPANY, OF PLAINVILLE, CONNECTICUT, A CORPORATION OF CONNECTICUT.

ROTARY SNAP-SWITCH.

No. 906,386.

Specification of Letters Patent.

Patented Dec. 8, 1908.

Application filed October 24, 1907. Serial No. 398,888.

To all whom it may concern:

Be it known that I, CHARLES A. CLARK, a citizen of the United States, and a resident of Hartford, in the county of Hartford and State of Connecticut, (whose post-office address is 62 Maple avenue, Hartford, Connecticut,) have invented certain new and useful Improvements in Rotary Snap-Switches, of which the following is a full, clear, and exact description, whereby any one skilled in the art may make and use the same.

The invention relates to switches for controlling circuits of electricity, and more particularly to the type of switches now well known in the art as a rotary snap switch. That is, a switch in which the stationary contacts are engaged by a contact bar which has a rotary quick release and engaging action.

20 The objects of the invention are to provide a simple, inexpensive device, having comparatively few parts, and with said parts arranged to give positive predetermined action with reference to the engagement and disengagement of the relatively stationary and movable contact members.

A further object is to provide a locking and releasing mechanism for the parts during rotation.

30 A still further object is to provide a switch actuating mechanism without the usual spring detents or pawls commonly employed.

Referring to the drawings: Figure 1 is a sectional view through a switch illustrating the improved mechanism. Fig. 2 is a detail plan view showing at 2^a the under side of the contact plate with the lock actuator at 2^b the locking plate and at 2^c the stop plate employed in the mechanism. Fig. 3 illustrates a bottom view of the parts shown in Fig. 2, the switch blade being broken away and a portion of the stop plate being broken away to show construction, the parts being in normal position. Fig. 4 is a view similar to Fig. 3 with the spindle and appurtenant parts turned through a portion of its movement. Fig. 5 is a view similar to Fig. 4 with the spindle turned still further. Fig. 6 illustrates the same parts after the contact plate and bar have moved ninety degrees. Fig. 7 is a detail bottom perspective view of the various parts of the mechanism showing at 7^a the stop plate, at 7^b the locking plate with interlock, at 7^c the contact actuating plate, at 7^d the spindle with the lock actu-

ator, at 7^e the spring clip of the spindle, at 7^f the spring, and at 7^g the contact bar. Fig. 8 is a sectional view showing a modified form of the device. Fig. 9 is a detail view in bottom perspective of the parts shown in Fig. 8 modification and illustrates at 9^a the locking plate with the interlock, at 9^b the contact actuating plate, and at 9^c the spring, the remaining parts are substantially the same as illustrated in the preferred form of the device.

In devices of this type it has been common to employ a ratchet and pawl with a pawl actuator suitably actuated from the spindle and arranged to release the pawl from the ratchet after the contact bar or its plate have been placed under predetermined tension of a spring. In such devices, so far as known, it has been necessary to employ a pawl controlled by a spring or some intermediate member and such devices have had the objection of uncertainty in their action.

It is one of the intentions of the present invention to do away with laterally moving pawls and provide for pure rotary movements between the various switch parts, at the same time providing an interlock which will permit the tensioning of the contact bar and its plate to effect a quick make and break action of said bar with reference to the stationary contacts of the circuit to be controlled.

To provide against the objectionable features heretofore named and secure a mechanism in which the various operating parts will be positively locked in predetermined positions, there is employed a stop plate for determining the movement of said parts, a locking plate for interlocking the contact bar until it has been placed under a predetermined tension, a contact plate co-operating with the locking plate and a lock actuator for actuating the locking plate. All of these parts are illustrated in bottom plan view in Fig. 2 at 2^a, 2^b and 2^c, respectively, and are further illustrated through a full cycle of their movements in Figs. 3 to 6 inclusive of the drawings.

In the accompanying drawings, the numeral 1 denotes a suitable base of insulating material having a suitably formed recess 2, within which the angularly formed base 4 of a stop plate 5 is mounted and held against rotation. The stop plate 5 has at its lower

end a tubular projection 6 suitably engaged by a locking nut 7 to hold the plate in the recess 2. This tubular projection and stop plate form a bearing for the switch spindle 8. The stop plate 5 has lobes 9 arranged in suitable number to provide for stopping and locking the switch blade, as hereinafter described.

Loosely mounted upon a spindle 8 is a contact actuating plate 10 provided with downwardly extending lugs 11 and 12 arranged in the path of the circle, the center of which circle is without the center of the spindle 8. It will thus be seen that the circle including said lugs is eccentric to the spindle 8 which passes through the contact actuating plate 10 and forms the center of rotation for said plate. The plate 10 is preferably formed of sheet metal with the lugs 11 and 12 stamped up thereon.

Below the contact actuating plate 10 is arranged a locking plate 13 having a peripheral curvature 14 conforming to the circle defined by the lugs 11 and 12 of the contact actuating plate. This locking plate has a central opening 15 within which is mounted a lock actuator 16, the lock actuator being secured to the spindle 8. The lock actuator 16 has a lug 17 which extends within an opening 18 formed on the inner wall of the locking plate in the opening 15.

Below the locking plate 13 is arranged the stop plate 5 which, of course, is fixed against rotation with reference to the spindle and is engaged by an interlocking cam 19 extending below the surface of the locking plate 13 and engaging the peripheral surface of the stop plate and its lobes 9.

To better understand the operation of the device illustrated in Figs. 3 to 6 inclusive, it must be first understood that the center of rotation of the contact plate 10 is coincident with the center of the spindle. It must be further noted that the peripheral surface of the locking plate 13 which presses against the lugs 11 and 12 of the contact plate has its center of generation at the point X, as indicated on the contact actuating plate 10, which center is exterior to the center of the spindle and consequently the center of rotation of the contact actuating plate. It must also be understood that the locking plate receives its movement from the turning of the switch spindle through the interengagement of the lug 17 with the recess 18.

With the above understanding, reference is made to Figs. 3 to 6 of the drawings. In Fig. 3 the parts are shown in normal position, it of course being understood that a spring 21 is arranged intermediate the spindle 8 and the contact actuating plate 10, so that the rotation of the spindle when said contact plate is held from rotation will place the spring under considerable tension and will be effective for quickly moving the

contact plate and its contact bar as soon as said plate is released, as hereinafter defined.

The interlocking lug 19 of the locking plate 13 is of considerable length and has an outer curved surface conforming to the lugs of said locking plate, while its inner curved surface is such as to ride along the periphery of the lobes of the stop plate 5. This interlocking lug 19 lies between the periphery of the stop plate 5 and the lug 12 of the contact plate. Obviously, as the spindle 8 is rotated the locking plate 13 will be moved within the path defined by the lugs 11 and 12 through the medium of the lock actuator 17 and the co-operating recess 18. As the center of the contact plate is coincident with the center of the spindle, said contact actuating plate 10 cannot rotate during a partial movement of the locking plate and its interlocking lug 19. The parts during said movement are represented in Fig. 4 of the drawings.

The interlocking action of the lug 19 is maintained until said lug reaches a point at the outer end of one of the lobes of the stop plate 5, whereupon the contact actuating plate being under tension and the interlocking lug 19 having passed to a point to clear the outer end of the lobe 9 of the stop plate, both the locking plate and the contact plate will be moved forward together, the latter moving about the locking plate until said locking plate and contact actuating plate assume the position indicated in Fig. 6 of the drawings. This latter figure with reference to Fig. 3, shows the parts moved through one complete cycle of operations with the contact bar turned through ninety degrees. The parts are now ready for a further movement of ninety degrees, thus a step by step movement causes engagement and disengagement of the contact bar 22 with the stationary contacts 23-24.

As shown in Fig. 1 the contact bar 22 is preferably formed of two parallel members which are completely insulated from the contact actuating plate 10 and spindle 8 and form open jaws 25-26 for engaging knife edges 27-28 of the stationary contacts. Obviously, these contact bars and stationary contacts may be arranged in any suitable number and juxtaposition to provide for the exigencies of any particular case, and may be arranged for single pole, double pole, or in fact, any desired form of switch mechanism.

It will be seen from the above description that there are no transversely movable pawls or spring detents and no ratchet mechanism of more or less delicate construction. The entire movements of the parts are purely rotary, one with reference to the other, and the locking of the contact plate is positive and is maintained until the interlocking plate has been moved to a position with ref-

erence to the contact plate and stop plate which permits both the locking plate and contact actuating plate to move together. All of the various parts may be stamped or pressed up and thus the parts of the device may be made with great accuracy and most economically, and may be assembled with the greatest facility. Attention is also called to the very compact nature of the entire mechanism.

The feature of compactness is further exemplified in Figs. 8 and 9 which show a slightly modified form of the device. In these figures the numeral 50 denotes the base 15 of insulating material, having secured thereto the stationary contacts 51—52, which are engaged and disengaged by the relatively rotary contact 53. This contact 53 is secured to and moves with a contact actuating plate 54 which has struck up from it, or otherwise formed thereon, lugs 55—56—57 and 58 which form the eccentric path or guide for the locking plate 59. The locking plate 59 has upon its lower side the interlocking lug 60 which cooperates with the lug 58 of the contact actuating plate and the stop plate 61 to prevent the movement of said contact plate until a spring 62 having one end secured to the contact actuating 20 plate and the opposite end secured to the spindle is properly tensioned. The stop plate 65 is identical in form with the similar part heretofore described in connection with Figs. 1 to 7 inclusive. The spindle 25 and actuator are also identical in form.

It will be noted that the cup-like locking plate 59 and the down-turned lugs of the switch actuating plate form a receptacle, within which the spring 62 may be located. 40 Thus all of the working parts including the lock actuator 66 are thoroughly inclosed, and all of the parts may be seated within a recess 67 formed in the block of insulating material. It will also appear that there are 45 no springs or other working parts extending above the contact actuating plate, and special advantages may be gained in having all of the various parts inclosed by the insulating material.

50 Obviously, the various details of the mechanism might be varied to a considerable extent without departing from the spirit or intent of the invention.

What I claim as my invention and desire 55 to secure by Letters Patent is:

1. In a rotary snap switch, a rotary spindle, a stationary stop plate, a contact actuating plate rotarily mounted on the spindle and bearing an eccentric seat, an eccentric 60 plate mounted to rotate in said seat and provided with a locking member intermediate the seat and the stop plate, means for rotating said eccentric plate and locking member with reference to the stop plate and eccentric seat and resilient means intermediate 65

the spindle and contact actuating plate for rotating the latter and causing movement of the eccentric plate.

2. In a rotary snap switch, a spindle, a stop plate having lobes, a contact actuating plate rotarily mounted upon the spindle and provided with an eccentric seat, said eccentric seat and lobes of the stop plate providing a path for the movement of an interlocking member, said interlocking member 70 arranged upon and moving with an eccentric plate mounted to rotate in the eccentric seat, means intermediate said plate and spindle for moving the former a predetermined distance and resilient means intermediate 75 the spindle and contact actuating plate for moving the latter and the eccentric plate after a predetermined movement of the interlock.

3. In a rotary snap switch, a fixed stop 80 plate having lobes, a rotary spindle, a plurality of rotary plates operatively mounted with reference to said spindle, one of said plates being eccentric relative to the spindle, and the other bearing an eccentric seat for 85 the said eccentric plate, means intermediate the spindle and eccentric plate for rotating the latter in its seat, means borne on and moving with said eccentric plate for releasing the plate bearing the eccentric seat 90 upon a predetermined degree of rotation of the eccentric plate with reference to the lobes of the stop plate and resilient connections intermediate the spindle and said 95 seat bearing plate.

4. In combination in a switch mechanism a stop plate, a spindle rotarily mounted with reference thereto, a contact actuating plate rotarily mounted with reference to the spindle and bearing an eccentric seat, an eccentric locking plate mounted in said eccentric seat, an interlocking lug appurtenant thereto, means intermediate the spindle and eccentric locking plate for rotating the latter in its eccentric seat and resilient means connecting the spindle and contact actuating 100 plate.

5. In a rotary snap switch, a fixed stop 110 plate having lobes, a spindle rotarily mounted with reference thereto, a contact actuating plate provided with a seat eccentric to the spindle and so associated with the lobes of the stop plate as to form a path for the movement of the interlocking member, an eccentric plate rotarily mounted in the eccentric seat and provided with an interlocking member arranged to move between said seat and lobes of the stop plate and connections intermediate the spindle and eccentric plate for moving the latter.

6. In a switch mechanism a stop plate, a spindle rotarily mounted with reference thereto, a contact actuating plate mounted to rotate about the spindle and provided with an eccentric seat, an eccentric plate 120

125

130

- mounted to be rotated in said seat by the spindle and bearing an interlocking member having interlocking and releasing actions with reference to said contact actuating plate upon a predetermined rotary movement with reference thereto, and means for simultaneously rotating the contact actuating plate and the eccentric plate upon a predetermined movement of the interlocking member.
7. In combination in a switch mechanism a contact actuating plate bearing an eccentric seat, an eccentric plate mounted to rotate therein, a spindle having a resilient connection with the contact actuating plate and having means for rotating the eccentric plate, an interlocking member borne upon the eccentric plate and preventing movement of the contact actuating plate during a predetermined movement of the spindle and means for moving the contact actuating plate on its axis of rotation about the eccentric plate after predetermined movement of the interlocking member.
25. 8. In a rotary snap switch, a fixed stop plate, a spindle rotarily mounted with reference thereto, a contact actuating plate pro-

vided with an eccentric seat, an eccentric mounted therein and surrounding the spindle, and an interlocking member borne upon 30 said eccentric.

9. In a rotary snap switch, a fixed stop plate, a spindle rotarily mounted with reference thereto, a contact actuating plate provided with an eccentric seat, an eccentric 35 mounted therein and surrounding the spindle, and a loose connection intermediate the spindle and eccentric for moving the latter.

10. In combination in a switch mechanism, a stop plate, a spindle rotarily mounted 40 with reference thereto and bearing a projection, a contact actuating plate rotarily mounted with reference to the spindle and bearing an eccentric seat, an eccentric locking plate mounted in said eccentric seat 45 bearing an interlocking lug and adapted to be rotated by the projection of the spindle and resilient means connecting said spindle and contact plate.
